UNITED STATES PATENT OFFICE.

JOHN MITCHELL AND JOHN CECIL GEORGE COSSEY, OF LONDON, ENGLAND.

COUPLING FOR RAILWAY AND LIKE VEHICLES.

Application filed August 14, 1922. Serial No. 581,885.

To all whom it may concern:

Be it known that we, JOHN MITCHELL and JOHN CECIL GEORGE COSSEY, both subjects of the King of Great Britain, residing in London, England, have jointly invented certain new and useful Improvements Relating to Couplings for Railway and like Vehicles, of which the following is a specification.

10 In the copending application, Serial No. 578,730, a coupling for railway and like vehicles is described in which a separate member interposed between the coupler head and the drawbar permits relative deflection between these parts in two planes mutually at right angles. This member is adapted to slide in a ferrule, surrounding the drawbar, inserted in the headstock or in a box member secured to the longitudinals or head-
15 stock, means being provided to prevent relative rotation between the coupler head and the drawbar.

20 A main spring and a subsidiary spring support and centralize the coupler head and 25 take up the initial draft stresses; further draft and all buffing stresses are taken up by the main spring.

25 The present invention consists in a modification or improvement of the arrangement 30 described in this prior specification.

35 According to the invention, in order to facilitate the passage round curves, the member acting as a universal joint is extended rearwards so that the vertical pin is behind the headstock instead of in front of it as in the previously described constructions. The vertical pin is in front of the box member containing the draft and buffing spring and the drawbar.

40 The box member is secured to the longitudinals and may be placed at any required position between the headstock and the centre of the longitudinals.

45 Between the buffer head and the ferrule inserted the front end of the box member and acting as a guide for the drawbar there is provided a hollow distance piece surrounding the extended portion of the intermediate member between the vertical and horizontal pins, the latter of which is arranged as in the examples shown in said copending application in front of the headstock. The distance piece is supported at the headstock and is free to move in a horizontal plane about the vertical pin behind the headstock.

The accompanying drawing shows in longitudinal vertical section an example of a construction according to the invention, the construction being split with the lower end 60 shown beside the upper portion to enable the drawing to be on a sufficiently large scale for clearness.

A is the buffer or coupler head, B the headstock, b a guide attached to the longitudinals or headstock or to both supporting the distance piece but allowing free movement in a horizontal plane about the pin M; C the drawbar, D the buffing and draw spring surrounding the shank of the drawbar, E a box-shaped member secured to the longitudinals K, F the intermediate member forming by means of the pins L and M a universal joint between the head and the drawbar. 70

75 A relatively light spring G abuts against a ferrule H surrounding the reduced end c of the drawbar, the flange h of the ferrule forming an abutment for one end of the spring D.

80 The other end of the spring G engages with a ferrule I on the reduced end c of the drawbar, and the other end of the spring D engages with a ferrule N inserted in the front wall of the box E and forming a guide 85 for the drawbar C. The springs D and G are compressed by the ferrules H and I by means of a nut J threaded on the end of the drawbar, initial compression of the spring D being obtained as described in the main 90 specification.

95 O is a distance piece surrounding the extended portion of the member F between the pins L and M, and transmitting buffing stresses from the coupler head A to the ferrule N. The distance piece O passes through an aperture provided in the headstock B and serves as a guide and support for the front end of the member F.

Having thus described the nature of the 100 said invention and the best means we know of carrying the same into practical effect, we claim:—

1. In railway and like vehicles a coupler head, a drawbar, an intermediate member 105 interposed between said coupler head and said drawbar, means provided in said member permitting movement in two planes mutually at right angles between said drawbar and said coupler head, framing secured to 110 said vehicle, front and rear plates secured to said framing, a flanged ferrule inserted in

- each of said plates and surrounding and guiding said drawbar, a draft and buffing spring abutting against the flanges of said ferrules and a distance piece disposed between said front ferrule and said coupler head and surrounding the greater portion of the length of said intermediate member.
2. In a railway and like vehicles a coupler head, a drawbar, an intermediate member interposed between said coupler head and said drawbar, pins respectively at the front and rear of said member permitting movement in two planes mutually at right angles between said drawbar and said coupler head, framing secured to said vehicle, front and rear plates secured to said framing, a flanged ferrule inserted in each of said plates and surrounding and guiding said drawbar, a draft and buffing spring abutting against the flanges of said ferrules, a headstock and a hollow distance piece disposed between said front ferrule and said coupler head passing through said headstock and forming a guide for said intermediate member.
- 10 3. In railway and like vehicles a coupler head, a drawbar, an intermediate member interposed between said coupler head and said drawbar, pins respectively at the front and rear of said member permitting movement in two planes mutually at right angles between said drawbar and said coupler head, framing secured to said vehicle, front and rear plates secured to said framing, a flanged ferrule inserted in each of said plates and surrounding and guiding said drawbar, a draft and buffing spring abutting against the flanges of said ferrules and a distance piece disposed between said front ferrule and said coupler head and surrounding the greater portion of the length of said intermediate member.
- 15 4. In railway and like vehicles a coupler head, a drawbar, an intermediate member interposed between said coupler head and said drawbar, means provided in said mem-

ber permitting movement in two planes mutually at right angles between said drawbar and said coupler head, framing secured to said vehicle front and rear plates secured to said framing, a flanged ferrule inserted in each of said plates and surrounding and guiding said drawbar, a draft and buffing spring abutting against the flanges of said ferrules, a headstock and a hollow distance piece disposed between said front ferrule and said coupler head passing through said headstock and forming a guide for said intermediate member.

20 5. In railway and like vehicles a coupler head, a drawbar, an intermediate member forming a universal joint between said headstock and said drawbar, a ferrule at the front end of said drawbar, a draft and buffing spring in said drawbar, a draft and buffing spring in said casing and a distance piece between said ferrule and said coupler head transmitting the buffing stresses to said spring.

In testimony whereof we have signed our names to this specification.

JOHN MITCHELL.

JOHN CECIL GEORGE COSSEY.
